EX

DESIGN FOR A GATE.

Design No. 12,874, dated April 11, 1882.

UNITED STATES PATENT OFFICE.

HENRY FALLER, OF MIDDLE VILLAGE, ASSIGNOR TO JOHN TIMMES, OF BROOKLYN, NEW YORK.

DESIGN FOR A GATE.

SPECIFICATION forming part of Design No. 12,874, dated April 11, 1882.

Application filed February 24, 1882. Term of patent 7 years.

To all whom it may concern:

Be it known that I, HENRY FALLER, a citizen of the United States, residing at Middle Village, in the county of Queens and State of New York, have invented a new and original 5 Design for a Gate, of which the following is a specification, reference being had to the accompanying drawing, forming part thereof.

This invention relates to a new and ornamental design for gates, as fully described in the following specification, and illustrated in the accompanying drawing.

The drawing shows a face view of my design.

In this drawing the letter A designates the 15 arched top bar, from the ends of which rise the arabesques B B, while its center supports an arabesque, C, composed of leaves a, two scrolls, b b, one on each side of the leaves a a, curved bars c c, which extend from the top of 20 the scrolls, and are ornamented by beads d, leaves e e, extending from the outer edges of the scrolls beneath the curved bars c c, and leaves f f, which extend from the central leaves, a, to the curved bars c c, and thence terminate 25 in scrolls resting upon the top bar, A. From the bottom edge of the top bar, at or near the center of its length, depend leaves g, from which is suspended a loop, h, and from the opposite sides of this loop extend curved bars 30 i i, which terminate in leaves j. From the sides of these curved bars i i extend ornamental scrolls k k, from the centers of which is suspended a shroud, l. Below the orna-

mental scrolls k k are leaves m m, and the outer edges of said scrolls and leaves bear against 35 curved bars n n, which extend from top bar, A, down to scrolls o o, and which are ornamented by beads p. The scrolls o o rest upon the lower bar, D, of the gate, and from them extend leaves q q, which fill the spaces between 40 the curved bars n n and the uprights E E of the gate. The ends of the lower bar, D, are ornamented by rosettes r r, and to the bottom edge of this bar are attached a series of ornamental escutcheons, s s.

What I claim as new, and desire to secure by Letters Patent, is—

1. The new and ornamental design of the arched top bar, A, of a gate and the arabesque C, composed of leaves a, scrolls b b, curved 50 bars c c, and leaves e e f f, as shown and described.

2. The new and ornamental design, consisting of the top bar, A, of a gate, the leaves g, depending from the bottom edge of said top 55 bar, the loop h, curved bars i i, leaves j and m, scrolls k k, and shroud l, as shown and described.

In testimony whereof I have hereunto set my hand and seal in the presence of two sub- 60 scribing witnesses.

HENRY FALLER. [L. S.]
